UNITED STATES PATENT OFFICE

HENRY A. STRINGFELLOW, OF PHILADELPHIA, PENNSYLVANIA, ASSIGNOR TO SOUTH-WARK FOUNDRY & MACHINE COMPANY, OF EDDYSTON, PENNSYLVANIA, A CORPORATION OF PENNSYLVANIA

CABLE SHEARING MECHANISM

Application filed December 31, 1930. Serial No. 505,838.

My invention relates to cutting or shearing mechanism and the object of my invention is to provide simple and efficient means for shearing heavy wire rope or cable.

5 A further object of my invention is to provide such shear mechanism with a plurality of clamping devices disposed on opposite sides of the shear blades; one of said clamping devices serving as a fixed element during 10 the shearing action and engaging the portion of cable from which a length is being sheared.

A further object of my invention is to provide a form of movable clamp made up of 15 a plurality of movable jaw members which may be placed in clamping position with respect to the section of cable to be sheared from the main section; certain of said movable jaw clamping members being carried 20 by levers which are detachably connected together by a link that may be opened or displaced for the positioning of the cable or rope to be cut, and one of said jaw members being actuated by fluid pressure means.

25 A still further object of my invention is to provide means whereby said movable clamp may be moved by or with the shear mechanism carrying the moving shear blade so that the section of cable or rope being sheared 30 will be positively moved as it is being sheared whereby a cut at a right angle to the axis of the rope or cable may be made and avoid the dislocation of the individual wires of the strands which make up such rope or cable 35 and which are usually distorted and tend to basket when wire rope or cable is sheared in the usual manner.

And a still further object of my invention is to provide filling pieces or inserts for the 40 body of the cable, which filling pieces are wedge shape in cross-section and are adapted to lie in the grooves or spaces between the strands of the rope or cable on that portion of the latter held by the clamps, (and in 45 some instances at the point of cutting) thus permitting the development of a more uniform pressure around the separate strands and holding the rope or cable more firmly in the clamps and at the point where the cooperating shear blades effect the desired cut.

These and other features of my invention are more fully described hereinafter; reference being had to the accompanying drawings, in which:

Figure 1 is a longitudinal elevation of 55 shearing mechanism within the scope of my invention, showing the movable clamp in the closed position.

Fig. 2 is a sectional elevation on the line 60 II—II, Fig. 3, of the means for closing the movable clamp; the latter being shown in the open position.

Fig. 3 is a plan view of the shearing mechanism on a slightly larger scale.

Fig. 4 is a sectional elevation on the line 65 IV—IV, Fig. 3, on the same scale as Fig. 3.

Fig. 5 is a cross sectional view on the line 70 V—V, Fig. 3, on the same scale as Fig. 1, and

Figs. 6, 7 and 8 are views illustrating a detail of my invention.

In the cutting of heavy cable and rope made from wire great difficulty is encountered because of the nature of the material operated upon. The wires making up the 75 strands of the cable individually tend to untwist as soon as severed resulting in what is known as basketing.

Up to the present time it has not been possible to shear heavy wire rope or cable 80 at a right angle to the axis of the same, for several reasons. In the first place it has been difficult and relatively impossible to secure sufficient clamping pressure to hold the rope or cable while being sheared. Secondly, on account of the twist put in the rope when it is made, the individual wires of the respective strands slip and untwist in the cutting operation. As a result of these conditions all attempts to make square cuts 85 through heavy cable or rope of wire result in diagonal cuts with the ends of the individual wires splayed and ragged.

In the improved mechanism which I have devised, I employ a fixed and a movable 90 shear blade of more or less usual type, with which a fixed clamp and a movable clamp for the wire rope or cable are employed. The fixed clamp, which may be in the form of vertically split jaws of usual type, is dis- 100

posed adjacent to and serves to hold the rope or cable at or adjacent to the stationary shear blade, while the movable clamp is arranged for movement simultaneously with the movable shear blade and carries the section of wire rope or cable with it as it is sheared.

In the drawings 1 represents the frame of the machine having a portion 2 forming a cylinder for a ram or plunger 2^a connected 10 to and operating a cross-head or frame 3 carrying the movable shear blade, indicated at 4. The fixed shear blade is indicated at 5, and may be mounted on the portion 6 of the frame. Between the portions 2 and 15 6 of the frame, space is left for the placement of the rope or cable to be sheared. Both shear blades are recessed as indicated at 4^a and 5^a respectively; such recesses approximating one half the diameter of the rope or 20 cable to be sheared and it will be understood that blades having recesses approximating one-half the diameter of the rope or cable to be sheared will be employed for the variously sized ropes or cables; such blades 25 being detachably mounted upon their respective supports or carriers.

The clamping means for the cable are arranged on opposite sides of the shear blades 4 and 5. The movable jaw of the so-called 30 fixed clamp is indicated at 7, and the fixed jaw of such clamp is indicated at 8; the jaw 7 being carried by a cross-head 7^a of a frame 9 which includes a pair of cylinders 9^a disposed for the reception of a pair of rams 9^b 35 and arranged alongside that part of the frame through which the ram 2^a, within the cylinder 2 extends, and which controls the operation of the cross-head or frame 3 carrying the movable shear blade 4.

40 The so-called movable clamp is mounted adjacent to the shear blades at the side of the same opposite the so-called fixed clamp. This movable clamp is made up of a plurality of independently mounted jaws 10, 11, 12 45 and 13, arranged to be held in clamping position with respect to the rope or cable to be sheared; such jaws having beveled meeting faces and concave surfaces for engagement with the rope or cable. The jaw 10 50 is removably carried by a head 14 adapted to a suitable slideway formed in the frame of the machine and its outward movement is limited by a bolt 15 connected to the cross-head or carrier 3 for the movable shear blade.

55 This jaw or clamping member 10 is adapted to a slideway in the head 14 and may be held in place by means of side plates 10^a secured to such head by screw bolts 10^b. The jaws 11 and 12 are pivotally connected at 60 11^a and 12^a respectively, to levers 16 and 17 fulcrumed at 16^a and 17^a to a sliding head 18 movably mounted with respect to the sliding head 14. The jaw 13 is removably supported by a link 19 pivoted at 19^a to the lever 17; 65 such link being detachably connected to the

lever 16 by a removable pin 20; such parts being secured together after the rope or cable to be sheared has been positioned within the jaws. The jaw 13 is mounted in a manner substantially like the jaw 10, and is retained in place by slide plates 13^a secured to said link 19 by screw bolts 13^b.

The head 18 is recessed to provide a cylinder 18^a for the reception of a ram or plunger 14^a connected to the head 14; the opposite end of said plunger being connected to a bolt 21 which extends through the head 14 and is operatively associated with a spring 22 disposed between said head 18 and a collar 21^a on the outer end of such bolt. 70 The function of said spring is to hold this clamp in the open position as indicated in Fig. 2. When the clamp is to be closed, fluid pressure may be admitted to the cylinder 18^a via pipe *a* and reacting upon the end wall of the same will cause the head 18 to move to the left bringing the clamping jaws into engagement with the rope and holding the same until the clamp as a whole is moved by the cross-head carrying the movable shear blade. The closed position is shown 80 in Fig. 1.

Carried by the foot or base of the head 14 I have provided adjustable members which may be in the form of threaded bolts 25 disposed lengthwise of the same. The ends 25^a of these bolts, adjacent to the moving cross-head carrying the movable shear blade 4 are so positioned that when such movable shear blade begins its cut, the cross-head 3 carrying the same contacts with the ends 25^a of said bolts 25 and imparts movement to the sliding head 14 and the head 18 so that as the cut progresses these heads, which together support the movable clamp, move so that the clamp may carry the portion of rope or cable sheared from the section which is held by the fixed clamp; the movable section of which has moved simultaneously with the movable shear blade 4 or in advance of such movement, so as to firmly clamp the rope or cable at the opposite side of said shear blades, as the cut progresses.

It will be understood, of course, that the several jaws 10, 11, 12 and 13 are replaceable by other jaws whose contacting faces are recessed to such an extent as to properly conform to the rope or cable being sheared. The levers 16 and 17 are pivotally carried by adjustable blocks so that when the jaws are changed their position with respect to the rope to be clamped, may also be adjusted.

The rope or cable to be sheared is provided with a suitable wrapping adjacent to or at the point at which the cut is to be made, and in order that the clamps may be assisted in their holding action, I preferably employ wedge-shaped inserts 26, as shown in Fig. 6, which may lie in the grooves of the rope or cable between the respective strands of

130

the same, as clearly indicated in Figs. 7 and 8. If desired these inserts may be employed at the point where the cable is cut and, if necessary, they may be tied in place.

5 The jaws of the movable clamp may be separated by exhausting pressure from the cylinder 18* thereby permitting the spring 22 to act upon the head 18 carrying the levers 16 and 17 and link 19 to which the 10 jaws 11, 12 and 13 are operatively connected. The sheared section of rope or cable may be removed from the movable clamp after the pin 20 connecting the link 19 and lever 16 has been removed so that said parts 15 may be opened, as indicated by dotted lines Fig. 2, or such sheared section may be slid lengthwise of the same away from the clamp.

I claim:

20 1. In shearing mechanism for wire rope or cable, the combination of a fixed shear blade suitably supported, a movable shear blade, means for moving the same with respect to the fixed shear blade, fixed clamping means for the rope or cable to be sheared disposed on one side of said shear blades, and movable clamping means on the opposite side of said shear blades.

25 2. In shearing mechanism for wire rope or cable, the combination of a fixed shear blade suitably supported, a movable shear blade, means for moving the same with respect to the fixed shear blade, fixed clamping means for the rope or cable to be sheared disposed adjacent to the fixed shear blade, movable clamping means disposed adjacent to the movable shear blade, and means whereby said movable clamping means moves simultaneously with the movable shear blade.

30 3. In shearing mechanism for wire rope or cable, the combination of a fixed shear blade suitably supported, a movable shear blade, means for moving the latter with respect to the fixed shear blade, a fixed clamp for the rope or cable disposed at one side of said shear blades, a movable clamp disposed at the opposite side of said shear blades and means whereby movement may be imparted to said movable clamp simultaneously with the shearing action.

35 4. In shearing mechanism for wire rope or cable, the combination of a fixed shear blade suitably supported, a movable shear blade, means for moving the latter with respect to the fixed shear blade, a fixed clamp for the rope or cable disposed at one side of said shear blades, a movable clamp disposed at the opposite side of said shear blades, a carrier for said movable clamp, and means whereby movement may be imparted to said carrier simultaneously with the shearing action.

40 5. In shearing mechanism for wire rope or cable, the combination of a fixed shear blade suitably supported, a movable shear blade, means for moving the latter with respect to the fixed shear blade, a fixed clamp for the

rope or cable disposed at one side of said shear blades, a movable clamp disposed at the opposite side of said shear blades, a carrier for said movable clamp, and adjustable means whereby movement may be imparted to said carrier simultaneously with the shearing action.

45 6. In shearing mechanism for wire rope or cable, the combination of shear blades mounted for operative action, clamping means for the rope or cable to be cut including a movable clamp; said clamp being sectional in form, means for holding a section of said clamp in relative position with respect to the rope or cable to be sheared, and means for moving another of said sections with respect to the first-named section to complete the clamping action.

50 7. In shearing mechanism for wire rope or cable, the combination of shear blades mounted for relative movement and operative action, a plurality of clamping means for the rope or cable to be cut including a movable clamp; said clamp being sectional in form, means for holding a section of said clamp in relative position with respect to the rope or cable to be sheared, and means for moving another of said sections with respect to the first-named section to complete the clamping action.

55 8. In shearing mechanism for wire rope or cable, the combination of shear blades mounted for relative movement and operative action, a plurality of clamping means for the rope or cable to be cut including a movable clamp; said movable clamp being sectional in form and one of said sections occupying a substantially fixed position, means for holding a plurality of said sections in relative position with respect to the rope or cable to be sheared, fluid pressure means for moving one of said clamping sections with respect to another to complete the clamping action, and spring actuated means for separating said clamping sections.

60 9. In shearing mechanism for wire rope or cable, the combination of a fixed shear blade, a movable shear blade, means for moving the latter with respect to the fixed shear blade, and movable clamping means for the rope or cable to be sheared disposed at one side of said shear blades.

65 10. In shearing mechanism for wire rope or cable, the combination of a fixed shear blade, a movable shear blade, means for moving the latter with respect to the fixed shear blade, movable clamping means for the rope to be sheared disposed at one side of said shear blades, and means whereby said movable clamping means moves simultaneously with the movable shear blade.

70 11. In shearing mechanism for wire rope or cable, the combination of a fixed shear blade, a movable shear blade, means for moving the latter with respect to the fixed shear

blade, a movable clamp for the rope to be sheared disposed at one side of said shear blades, and means whereby movement may be imparted to said movable clamp simultaneously with the shearing action.

12. In shearing mechanism for wire rope or cable, the combination of a fixed shear blade, a movable shear blade, means for moving the latter with respect to the fixed shear blade, a movable clamp for the rope to be sheared disposed at one side of said shear blades, a carrier for said movable clamp, and means whereby movement may be imparted to said carrier simultaneously with the shearing action.

13. In shearing mechanism for wire rope or cable, the combination of a fixed shear blade, a movable shear blade, means for moving the latter with respect to the fixed shear blade, a movable clamp for the rope to be sheared disposed at one side of said shear blades, a carrier for said movable clamp, and adjustable means whereby movement may be imparted to said carrier simultaneously with the shearing action.

14. In shearing mechanism for wire rope or cable, the combination of shearing blades, clamping means for the rope or cable, and shape-conforming inserts fitting the grooves of the rope or cable and cooperating with said clamping means during a cutting operation.

15. In shearing mechanism for wire rope or cable, the combination of shearing blades, a plurality of clamping means engaging the cable on opposite sides of said shearing blades, and shape-conforming inserts fitting the grooves of the rope or cable and cooperating with the several cable-engaging elements during a cutting operation.

In witness whereof I have signed this specification.

HENRY A. STRINGFELLOW.
